MEANS FOR REMOVING HEAT AND MOISTURE FROM THE PRESSING ELEMENTS OF LAUNDRY PRESSING MACHINES

Wallace F. Gayring, Minoa, N. Y., assignor to The Prosperity Company, Inc., Syracuse, N. Y., a corporation of New York

Application May 9, 1947, Serial No. 746,997

1 Claim. (Cl. 38—15)

1

This invention relates to means for removing heat and moisture from the pressing elements of garment or laundry pressing machines in which the work is moist when being pressed, and has for its object constructions by which the heat of the heated pressing elements is gently withdrawn, or deflected, from the pressing face of the upper pressing element when the press is open, away from the face of the operator and out of the room in which the machine is located, and also the heat and moisture withdrawn from the work and the padding of the lower pressing element when the press is both open and closed.

It also has for its object, a control of the heated air radiating from the pressing elements to reduce to a minimum the interchange of air between the pressing elements of the machine and the surrounding atmosphere, this being a desideratum when the machines are located in an air conditioned room, and to facilitate the drying of the article being pressed.

The invention consists in the novel features and in the combinations and constructions herein-after set forth and claimed.

In describing this invention, reference is had to the accompanying drawings in which like characters designate corresponding parts in all the views.

Figure 1 is a side elevation of one embodiment of a machine embodying this invention.

Figure 2 is an enlarged fragmentary elevation partly in section.

Figure 3 is an enlarged fragmentary sectional view of the lower pressing element and the padding thereon.

Figure 4 is a fragmentary rear elevation, partly in section, looking to the right in Figure 2.

Figure 5 is an inverted plan view of the lower pressing element.

The pressing machine and its operating mechanism may be of any suitable construction. It includes upper and lower pressing elements 1, 2, the upper pressing element being movable toward and from the lower. It is here shown as carried by the usual yoke or lever 3 pivoted at 4 to an upwardly extending arm 5 forming part of the frame 6 of the machine. This arm is actuated by any suitable actuating mechanism located within the frame 6. The frame is provided with a cabinet enclosing the mechanism. The lower pressing element 2 is mounted on a suitable support or gooseneck 7 which, in turn, is mounted on the top or table 8 of the pressing machine.

The invention includes a machine of this type having an opening and closing movement, with

the upper element having a hood enclosing the same and spaced therefrom providing a chamber open at the pressing face of the upper pressing element, the lower element being formed with a perforated top and a chamber below the top in communication with said perforation, and means for simultaneously creating vacuums in the hood and said chamber.

The invention of the machine further includes 10 providing the lower pressing element with a heating chamber around the margin only thereof on the under side of said margin in heat conducting relation therewith in order to not only facilitate the heating of the lower pressing element after the 15 machine is in operation, but also to heat incoming air drawn in during the suction operation, which incoming air passes through the pad, dries the same, and also keeps vaporized, or converts into vapor, moisture absorbed from the damp articles being pressed into the padding.

The upper pressing element is enclosed in a suitable hood 9 mounted thereon to move therewith, it enclosing a vacuum chamber 10 extending over and conforming to the upper pressing element 1, and the side walls thereof being spaced from the edges of the upper pressing element 1, at 11. The side walls are in a plane about flush with the pressing face 12 of the upper pressing element 1. The pressing element 1 is internally heated to keep the pressing face 12 hot. The hood 9 is provided with a heat insulating inner layer 13, and the edges of the side walls are covered by a channel shaped burn guard 14. The lower pressing element 2 is provided with a vacuum chamber 15 on the lower side thereof of its top plate which is perforated, this chamber terminating short of the marginal edges of the lower pressing element. The lower element is also provided with a padding which includes some sheets of materials that are capable of absorbing moisture.

As here shown, the padding includes a layer 16 of what is known as a spring padding, this being covered by a metal wire screen 17 on which is superimposed a layer 18 of steel wool, over which is laid a layer of cloth 19 which may be flannel, or fiber glass, and the whole being covered by a wrapper 20 of fibrous material, usually a cotton cloth, or of a nylon material. The wrapper 20 extends around the side edges of the padding and is secured at 21, around its edges, to the lower pressing element 15. The cover cloth is porous and hence, air can pass therethrough for a purpose to be presently described.

The lower pressing element is also heated, but 55 after the press is in operation it is heated addi-

tionally by heat from the upper pressing element during pressing operations.

One of the features of the invention is the heating of the lower pressing element around the margin only thereof, as by a heating chamber 22, this encircling the side walls of the vacuum chamber 15 and being in heat conducting relation to the margin of the top plate. Steam for heating is supplied to the upper pressing element through inlet and return pipes 23 and 24 from any suitable source, these pipes being heat insulated to prevent, as far as possible, the exchange of heat between them and the air of the room. The steam chamber 22 and the chamber 15 are insulated also by a covering 15a.

The steam is circulated from a suitable source to the marginal heating chamber 22 of the lower pressing element through an inlet pipe 25 and return pipe 26. The hood 9 is connected to a suitable source of vacuum as the intake end of an exhauster 27 through a header 28 on the hood 9 and communicating with the chamber 10 at two points, pipe 30 to a swivel coupling 31 located coaxially with the pivot 4, and pipe 32 to the intake side of the exhauster 27. The exhauster discharges through a pipe 33 outside of the air conditioned room. The bore 34 of the header 28 gradually increases in diameter from the end attached to the pipe 30 to the other end in order to more evenly distribute the pull of the vacuum within the hood 9.

The vacuum chamber 15 is connected to the intake side of the exhauster 27 by a header 35 opening at two points into the vacuum chamber 15, and a pipe 36 having a bend at 37 therein connected at 38 to the intake side of the exhauster 27. The exhauster is actuated in any suitable manner as by a motor 39, or several machines connected to a central vacuum system.

In operation, the blower rotates at such speed as to create a gentle vacuum or suction in the hood 9 sufficient only to deflect heated air from the pressing face 12 of the upper pressing elements into the hood 9 through the inlet 11, and also to deflect any uprising currents of air from the lower pressing element into the hood when the press is open. The vacuum is also sufficient only to deflect air currents down through the padding through spring pad section 16 and into the vacuum chamber and out through the exhauster, and also to create an in-draft of air through the edge portions of the cover cloth 20 through the spring padding 16, this air being heated by conduction from the marginal heating chamber 22. The air is thus heated to a sufficient extent to prevent condensation of the moisture within the pad so that it is withdrawn in vapor form through the vacuum chamber 15, pipe 36, and out through the exhauster 27, the suction being regulated so that there is a minimum of outside conditioned air displaced. The displacement of the air conditioned air is also minimized by the fact that the moisture for the most part makes up the body of air passing out through the exhauster, the vapor being generated from the moisture in the damp articles being pressed during the pressing operation. Ordinarily, the steam thus generated was allowed to escape into the room. To further minimize the exchange of air, the air supply may be from outside the air conditioned room.

This press is particularly applicable for air conditioned laundries without requiring a complete change over of the pressing machines for new cabinet types of machines especially built for air conditioned laundries.

In commercial laundries, the heated pressing machines are in effect heaters or stoves. In the spring and summer months, working in the room in which the pressing machines are located is extremely uncomfortable and at times almost unendurable and, under the labor situation prevalent now and during the past several years, laundrymen have experienced great difficulty in getting and retaining press operators in spite of high wages. It was found that operators preferred other jobs at much less pay, as clerks, etc., in air conditioned establishments. The cost of maintenance of air conditioning in the press rooms of laundries is prohibitive and reflects in an increase in the already excessive consumer cost of the laundered articles. The pressing machine equipment installed in laundries throughout the country is, for the most part, in good condition. It would be uneconomical and wasteful to junk this equipment to install new presses built especially for use in air conditioned press rooms even if the special machines were available and plentiful, and if business and financial conditions warranted the substitution. By this machine, the present press equipment can be modified at a comparatively small cost to be used in air conditioned press rooms by exchanging the upper and lower pressing elements for those of this invention with blower equipment. Part of the old equipment, as the head or upper element, may be used for another exchange by being equipped with a hood.

By this machine, heat and moist air due to the operation of the machine is discharged as such outside of the air conditioned room, and also may be used in heat exchangers. There is very little exchange of heat and air between the machines and conditioned air. Hence, the cost of maintenance of the air conditioning system is increased very little over that of a room of the same size not having the pressing machines therein. Owing to the construction of the lower pressing element, heat is not radiated therefrom into the room except to a small extent, and the air withdrawn by the vacuum in the lower buck is also minimized by the fact that it is loaded or made up, for the most part, of steam or vapor generated from the garment being pressed. At the same time, the heated air is deflected from the face of the operator due to both the vacuum in the lower element and the vacuum in the hood of the upper pressing element.

What I claim is:

A laundry press including upper and lower pressing elements, at least one having an opening and closing movement, the upper element being heated and having a hood enclosing the same and spaced therefrom providing a chamber open at the pressing face side of the upper pressing element, the lower pressing element being formed with a perforated top plate and a chamber below the top plate, and means for simultaneously creating vacuums in the hood and said chamber for withdrawing heat and moisture from and adjacent the pressing face of the upper pressing element away from the operator when the press is open, and also withdrawing heat and moisture from the work and from and adjacent the lower pressing element away from the operator when the press is both open and closed, said means including an elongated header extending longitudinally along the top of said hood inwardly of the sides and ends thereof and communicating at opposite ends with the chamber within the hood, and an elongated header extending longitudinally along the underside of the bottom

wall of the chamber below the perforated plate of the lower pressing member inwardly of the sides and ends thereof and communicating at opposite ends with said chamber at opposite end portions thereof.
